UNITED STATES PATENT OFFICE.

ORVILLE R. AIKMAN, OF SALEM, ILLINOIS.

STOVE.

Application filed August 30, 1922. Serial No. 585,232.

To all whom it may concern:

Be it known that I, ORVILLE R. AIKMAN, a citizen of the United States, and a resident of Salem, in the county of Marion and State 5 of Illinois, have invented certain new and useful Improvements in Stoves, of which the following is a specification.

This invention relates to stoves, and is more particularly directed to a stove adapted 10 for cooking or heating or for a combination of both of these functions, and in which kerosene or gas is employed as a fuel.

An object of the invention is the provision of a stove in which a complete combustion 15 of the fuel is had, thereby eliminating smoke and soot with a consequent reduction in the cost of operation.

A further object of the invention is the provision of a fire box adapted to become 20 incandescent under the action of a flame produced by kerosene or gas, with means for returning the heated gas at predetermined points within its circulation through the stove to the hottest portion of the stove 25 in order to obtain the greatest efficiency.

Another object of the invention is the provision of pilot currents formed from the 30 heated gases to aid in promoting the circulation of the gases through the stove where- by no pockets of dead gas are permitted to form in the circulatory system as the heated gases are advanced by stages through said system.

This invention will be best understood 35 from a consideration of the following detailed description in view of the accompanying drawings forming part of this application; nevertheless, it is to be understood that the invention is not confined to the disclosure, being susceptible of changes or modifications, but such changes or modifications 40 shall mark no material departure from the salient features of the invention as expressed in the appended claims.

Figure 1 is a vertical section of the stove 45 in elevation,

Figure 2 is a horizontal section taken along the line 2—2 of Figure 1 looking in the direction indicated by the arrows.

Figure 3 is a view in perspective of an inverted cone for diverting a portion of the gases when circulated through the stove,

Figure 4 is a view in perspective of a centrally disposed drum for effecting the circulation of the gases through the stove,

Figure 5 is a transverse horizontal section taken along the line 5—5 of Figure 1.

Referring to the drawings, 1 indicates an ordinary stove floor base mounted upon rollers 2. The floor base includes an integrally formed peripheral flange 3. Members 4 and 5 form a base portion resting on base 1. This base may be of highly polished iron or the same may be nickel-plated.

The member 5 is provided with doors 6 at diametrically opposite points, with sliding ventilators 7 on the doors for regulating the amount of air admitted to the burners.

Within the base member 5 there is mounted a burner 8 which may be of any approved construction, but I prefer to employ a burner adapted to use kerosene oil and which is capable of providing an intense heat for raising the temperature of a generator located within the fire box 9 and spaced above the burner 8 to an incandescent heat. The member 5 is provided with a central opening 10 leading into the fire box 9. The fire box is adapted to be secured to the base member 5 in the usual manner, the lower circular end of the fire box being seated within a flange 11 formed at the upper end of said base member.

The generator in the fire box is formed of a plurality of bars made of such metal or material that will withstand an intense heat without readily being destroyed. As shown in Figure 1, this generator is formed by bars which may be square or round with the first layer of bars 12 placed above the burner 8, located in the same horizontal plane, and spaced from each other with the opposite ends of the bars engaging the opposite side walls of the fire box 9. These bars 12 are supported by the side walls of the fire box.

Above the spaced bars 12, but running transversely of the same are another series of spaced bars 13 of similar construction with their opposite ends seated on and supported by opposite portions of the wall of the fire box. Resting on the transverse bars 13 is another series of spaced bars 14 of similar construction to the bars 12 and 13 and supported in a similar manner but located over the spaces between the bars 12 and transversely of the bar 13.

Other series of spaced bars located in the same horizontal plane and positioned transversely of the next lower series of bars are continued upwardly to a point which is ad-

5 jacent the refraction plate 15. These series of horizontal bars may be cast in one piece, or connected together in any approved manner, or instead of employing bars, perforated or slotted plates may be employed located in superimposed relation.

10 The refraction plate 15 is located midway between the top and bottom of the fire box 9 and supported by the side wall 10 of the fire box and above the generator, in the lower portion of said fire box. This refraction plate may be made of any material adapted to withstand an intense heat, and is formed of a circular convexed plate 15 with the central opening 16 and with a series of openings 17 adjacent its periphery where supported on the inner walls of the fire box.

20 Located adjacent the extreme upper end of the fire box 9 and secured thereto is an inverted member 18 in the shape of a frustum of a cone having a central opening 19 adjacent its lower reduced end, and which is opposite to the central opening 16 25 of the refraction plate 15. The reduced annular space 20 located between the outer side walls of the cone 18 and the inner walls of the fire box 9 is sealed from the space in the outer stove casing 21 which is 30 located above the fire box 9 and secured thereto in any approved manner.

35 Spaced from the large opening 22 of the cone shaped member 18 is the lower end of the drum 23 supported by the legs 24 upon the flange 25 projecting laterally inwardly from the casing 21. The lower end of the drum 23 is closed by a hemi-spherical member 26 which is formed integrally with the drum 23 and is provided with a central opening 27 for permitting a certain amount 40 of hot gases which have advanced to this point through the interior of the drum. The upper end of the drum 23 falls short 45 of the upper end of the casing 21 with a second inverted member 28 secured in any approved manner to the upper end of the casing 21 with its reduced end projecting into the drum 23. The hollow inverted member 28 being in the shape of a frustum 50 of a cone is provided with a reduced opening 29 located within the drum while the upper end of the inverted member which is of greater diameter than the opening 29, 55 leads into the hollow top section 30 of the stove. The inverted member 28 where connected to the section 30 and the casing 21 is sealed by means of rigid securing means to prevent any gas which has reached the reduced space 31 between the outer wall 60 of the inverted member 28 and the inner wall of the casing 21 from passing through this space to the compartment 32 of the section 30 of the stove. Above the chamber 65 32, there is provided a second chamber 33 which is formed by a sliding cover 34. The

chambers 32 and 33 are separated from each other by a partition 35 which is provided with a removable lid 36. The partition 35 and lid 36 provide means for supporting kitchen utensils for cooking purposes. 70

Leading into one side of the chamber 32 and through the section 30 of the stove is an exhaust pipe or flue 37 having a horizontal portion 38 extending within the chamber 32. The upper portion of the pipe 75 38 is cut away as shown at 39 in order to provide a greater opening through which the gases in the chamber 32 may escape to the pipe 37.

80 The circular concaved ring 40 is attached to or integrally formed with the fire box 9, and is adapted to force the heat outwardly from the exterior of the fire box. The under portion 41 of the upper section 30 of the stove is likewise adapted for the same 85 purpose.

90 In the operation of the stove, the burner is lighted with the sliding draft doors 7 positioned to admit the proper amount of air to the burner compartment 5. The 95 flame of the burner playing upon the generator in the fire box heats the bars 12, 13 and 14. The heated gases from the burner passing up through these bars which are located in staggered relation, is deflected 100 downwardly by the refraction plate 15 toward the generator. The heated gases then travel upwardly through the peripheral openings 17 with a portion of the same 105 passing through the opening 16 into the opening 19 of the inverted member 18. The portion of the heated gases passing through the opening 16 is what I term "a pilot current," since they promote circulation by inducing a flow of the heated 110 gases pocketed in space 20 from said space toward and through the inverted cone-shaped member 18.

115 The gases issuing from the opening 16 pass upwardly through the inverted member 18 and strike the hemispherical base member 26 of the drum 23. A portion of the gas passes through the central perforation 27 and acts as a pilot current for the rest of the gas when it reaches the space 31 between the inverted member 28 and the inner wall of the casing 21. 120

125 The remaining portion of the heated gases which strike the base member 26 are deflected downwardly and around the bottom peripheral edge of the drum 23 and upwardly through the space 42 formed between the outer wall of the drum 23 and the inner wall of the casing 21.

130 Due to the advancing pilot current from the opening 27, the heated gases which have reached the top of space 31 will be drawn downwardly and around the inclined sides of the inverted member 28 and through the opening 29 into the chamber 32 of the upper

section 30 of the stove, whence the gases will find their way through the extended opening 39 of the horizontal pipe 38 into said pipe and out through the tube 37.

5. A continuation of the burner raises the generator formed of the bars 12, 13 and 14 to an incandescence, with the heated gases being constantly deflected toward the hottest portions of the stove and through 10 which the heated gases are circulated whereby the greatest efficiency will be had.

It is to be understood that the generator, the refraction plate, inverted cone-shaped members, and the centrally disposed drum 15 may be readily placed within any ordinary heating stove or furnace now in use, with certain changes only in the dimensions in order to adapt the different parts of my improvement to the various sizes of said heating 20 plants. The fire box shell may be made of thinner material than that now employed and any shape or design of fire box may be used in connection with the generator.

25. The generator in combination with the deflectors provide in an efficient manner, a means for utilizing all the heating units of a fuel. The so called oil-gas burner which uses kerosene, gives the higher efficiency as 30 the blue flame leaps from the burner; while at a very short distance beyond this point, heating qualities of the flame are greatly diminished.

Since the generator is raised to a state of 35 incandescence at about the point where the flame of the oil burner begins to lose its heating value, the gases of combustion are raised to a high temperature by the generator. The refraction plate located just above 40 this generator is designed to deflect said gases toward the hot generator after they have passed through the same in order that the proper temperature of the gases may be maintained and that combustion may be 45 complete. The succeeding deflectors are for a like purpose, that is, to direct gases that have given up some of their heat to those regions of the stove or furnace which are hottest.

50. The members 18, 23 and 28 are intended to retard rapid upward circulation of the heated gases toward the flue and in order that the said gases will attain their full power of heating and give the best results.

55. I claim:

1. A stove comprising a fire box, a burner, means in the fire box adapted to be raised to a state of incandescence, means for concentrating the heated gases of combustion 60 from the burner upon the incandescent means and for causing a peripheral flow of the gases from the fire box, said concentrating means including means for causing a column of relatively small cross section 65 of the heated gases from the incandescent

means to be directed centrally upward, and means above the concentrating means for causing the peripherally flowing gases to be diverted towards the relatively small central column of gases and cooperating with said 70 column of gases for inducing a central flow of the peripherally flowing gases.

2. A stove comprising a fire box, a burner, means in the fire box adapted to be raised to a state of incandescence under the action of 75 the burner, a refraction plate for deflecting the heated gases from the fire box toward the incandescent means, said refraction plate being provided with a central perforation to provide a pilot current, and a series of peripheral perforations for producing peripheral currents of heated gases, and means located above the refraction plate for directing the peripheral currents of heated gases to the center of the fire box, with the pilot current cooperating to induce the flow of the peripheral currents toward the center of the fire box.

3. A stove comprising a fire box, a burner, means in the fire box adapted to be raised to a state of incandescence under the action 90 of the burner, means located above the incandescent means for dividing the gases of combustion into distinct streams of gases, and means for deflecting certain of the streams towards one of the other streams, a casing mounted on the fire box and adapted to conduct the heated streams of the combustion gases from the fire box.

4. A stove comprising a fire box, a burner, a generator in the fire box adapted to be raised to a state of incandescence under the action of the burner, a refraction plate for deflecting a portion of the heated combustion gases issuing from the generator back to the generator, a central perforation of the refraction plate adapted to form a pilot current with peripheral perforations adapted to form peripheral currents of combustion gases, an inverted hollow cone-shaped member for cooperating with the pilot current for diverting the peripheral streams of combustion gases into an opening in the lower end of the inverted member, a casing mounted on the fire box, a drum concentric within the casing and provided with means at its lower end for deflecting the heated gases passing through the inverted member toward the inner wall of the casing, and means connected with the casing for conducting heated gases from said casing.

5. A stove comprising a fire box, a burner, a generator in the fire box adapted to be raised to a state of incandescence under the action of the burner, means for deflecting the heated gases of combustion directly into the generator including means for dividing the gases of combustion into streams, means for causing the divided streams of the gases to move to the center of the fire box, means

above the fire box for deflecting the heated gases toward the fire box, a casing located on the fire box, means within the casing for causing a greater portion of the heated gases to be directed outwardly toward the inner wall of the casing, and means for conducting the heated gases away from the casing.

6. In a stove, a burner, a generator adapted to be heated to a state of incandescence under the action of the burner, and a refraction plate for deflecting the heated gases of combustion issuing from the generator back into the generator, said refraction plate comprising a convex member provided with a central opening and a series of peripheral openings whereby the heated gases striking the refraction plate are not only deflected, but are divided into a central stream and a plurality of peripheral streams.

7. A stove, comprising a fire box, a burner, a generator in the fire box adapted to be raised to a state of incandescence under the action of the burner and comprising a plurality of spaced bars located in a horizontal plane with spaced bars mounted transversely on the first mentioned bars, other series of spaced bars located in layers and supported by the first mentioned series of bars with one series of the bars disposed transversely with an alternate series of bars and means for directing a portion of the gases of the combustion chamber issuing from the spaced bars back upon said bars whereby said bars are raised to a state of incandescence.

8. A stove comprising a fire box, a burner, a generator adapted to be raised to a state of incandescence under the action of the burner, a refraction plate, a hollow inverted cone shaped member, a hemispherical member and a second inverted hollow cone shaped member with each of the members adapted to deflect the heated gases of combustion toward the next preceding member.

9. A stove comprising a body or casing, a burner, a generator in the body adapted to be brought to a state of incandescence by

the burner, a deflector adjacent the generator causing peripheral flow of gases, means for directing the peripherally disposed gases toward the center of the casing, means for causing the centrally conducted gases to be directed toward the inner wall of the casing, said means adapted to cause a centrally disposed flow of the gases upwardly through the casing, and means above the last mentioned means for directing the peripherally disposed gases toward the centrally disposed flow of gases, and means above the last mentioned means for permitting expansion of the gases.

10. A stove comprising a fire box, a burner, means in the fire box adapted to be raised to an incandescent state under the action of the burner, means for causing the products of combustion to be directed upwardly along the periphery of the fire box, means for causing the products of combustion to be returned to the center of the fire box, a pilot at the center of the fire box for aiding in directing the returned gases of combustion upwardly through the center of the fire box, means for causing the upwardly directed gases of combustion to be deflected downwardly, and means for causing said deflected gases of combustion to be directed upwardly and adjacent the periphery of the fire box.

11. A stove comprising a fire box, a burner, means in the fire box adapted to be raised to a state of incandescence under the action of the burner, means for concentrating the heated gases from the fire box upon the incandescent means and for causing a peripheral flow of said gases, means for deflecting the gases toward the center of the fire box and for causing said gases to move upwardly in expanded relation with the deflecting means, and a second deflector above the first deflecting means having an opening to permit the escape of a portion of the deflected gases upwardly and centrally of the fire box.

ORVILLE R. AIKMAN.
